Henry Cochrane, Philadelphia, Pa.

Application February 21, 1948, Serial No. 144,662

Term of patent 14 years

(Cl. D33—19)

To all whom it may concern:

Be it known that we, William Joseph Cochrane and Philip Henry Cochrane, citizens of the United States, and residents, respectively, of Wyndmoor, in the county of Montgomery and State of Pennsylvania, and of Philadelphia, in the county of Philadelphia and State of Pennsylvania, have invented a new, original, and ornamental Design for Child's Wardrobe, of which the following is a specification, reference being had to the accompanying drawing, forming part thereof.

The figure is a perspective view of a child's wardrobe, showing our new design.

We claim:

The ornamental design for a child's wardrobe, as shown.

WILLIAM JOSEPH COCHRANE.
PHILIP HENRY COCHRANE.
